UNITED STATES PATENT OFFICE

PERLEY R. GLASS, OF WAYLAND, AND JAMES E. MCINTIRE, OF PEABODY, MASSACHUSETTS, ASSIGNORS TO UNITED SHOE MACHINERY CORPORATION, OF PATERSON, NEW JERSEY, A CORPORATION OF NEW JERSEY

FOLDING MACHINE

Application filed January 16, 1926. Serial No. 81,814.

This invention relates to folding machines and is herein illustrated as embodied in a machine of the type disclosed in application Serial No. 35,111, filed June 5, 1925, in the name of James E. McIntire, for folding the margins of covers of book cases and similar articles over the backings upon which the covers are mounted.

In the manufacture of various types of books, pocketbooks, card cases and similar articles, it is customary to attach to the backing, by means of paste, a cover of leather or imitation leather the margins of which extend beyond the edges of the backing, and then to apply paste to these margins and fold them over upon the adjacent margins of the backing. For the performance of such operations, machines of the type referred to are provided with mechanism adapted for folding straight edges and square corners, and also with mechanism adapted for folding round corners. It is an object of the present invention to provide improved folding mechanism adapted for use in machines of the type disclosed in the application identified above, by the use of which folding operations may be still further facilitated, and in certain respects this invention consists in improvements in machines of the type referred to, although in various aspects the invention is not limited to embodiments in such machines.

In machines of the type shown in the application, the round corner folding mechanism comprises a work support, an edge guide extending above said support, a forming plate normally held above said support, and a folder movable over the top of the edge guide. In the operation of such a machine, the work is placed upon the work support with the projecting margin of the cover at a corner thereof resting upon the edge guide, and the forming plate is then brought down to cause said margin to be bent upward by the edge guide preparatory to being folded over the forming plate by the folder. According to one feature of the present invention, there is provided a novel folding mechanism organization in which the work support is yieldingly mounted and held nor-

mally with its surface substantially flush with the top of the edge guide so that, when the forming plate is brought down upon the work, which has been placed upon the work support, it first presses the work firmly against the work support and then pushes both the work and the work support down to cause the margin of the work to be bent upward. With this construction, the work is securely held during the bending up of the

55

80

When the forming plate of a machine of the type disclosed in the application referred to has been brought down in the manner described above to bend up the margin of the work and to clamp the body portion of the work upon the work support, the folder is caused to fold the bent margin over the edge of the forming plate, the work support is lowered slightly to relieve the pressure of the forming plate upon the work, and the forming plate is withdrawn from beneath the folded over margin of the work preparatory to the pressing of the fold. According to another feature of the present invention, a presser foot for engaging the body portion of the work is associated with the forming plate, and yielding means are provided for causing the presser foot to follow the work support in its downward movement so that the work is securely held during the withdrawal of the forming plate.

Other features of the invention relate to improved mechanism for folding the entire margin of comparatively small oblong book cases having round corners, to improved mechanism for folding square corners and to presser fingers associated with the straight edge folding mechanism.

These and other features of the invention including certain details of construction and combinations of parts will be described as embodied in an illustrative machine and pointed out in the appended claims.

Referring now to the accompanying drawings,

Fig. 1 is a perspective of a machine in which the present invention is embodied;

Fig. 2 is a vertical longitudinal section through the machine;

100

Fig. 3 is a perspective of the upper portion of the machine viewed from a different angle from that chosen in Fig. 1;

5 Figs. 4 and 5 are perspectives of the mechanism for forming a preliminary bend in the margin of the cover at a square corner thereof, Fig. 4 showing the position of parts before the work is operated upon and Fig. 5 after it has been operated upon;

10 Fig. 6 is a perspective of the folder of the mechanism for folding round corners;

Fig. 7 is a detail principally in section showing the mounting of the forming block;

15 Fig. 8 is a perspective of a piece of work showing its condition after having been operated upon by the mechanism shown in Figs. 4 and 5;

Fig. 9 is a perspective of a square corner after it has been completed by being folded;

20 Figs. 10, 11, 12 and 13 are views partly in elevation and partly in section showing more particularly the position of the work engaging parts of the round corner folding mechanism during successive stages in the folding of a round corner, the corner guides having been omitted to promote clearness; and

25 Figs. 14, 15 and 16 are perspectives showing successive stages in the folding of a comparatively small oblong book cover having round corners.

Referring first to Figs. 14, 15 and 16, the case of a book comprises commonly a backing in the form of two boards 100 which may be of cardboard, heavy paper or other suitable material and a cover 200 which may be of any flexible material and is commonly leather or imitation leather. There are thus four straight edges and four round corners to be folded. Where round corners are desired in the completed case, the boards are cut with rounded corners and the cover with similarly rounded corners, the margin of the cover projecting beyond the edges of the boards; and when a corner of the cover is folded over a corner of a board, the corner of the cover should be plaited as evenly as possible, as indicated at 300 in order that the corner of the finished case may be free from bunches.

35 With the illustrated machine, work having round corners is usually presented four times in succession to round corner folding mechanism and then four times in succession to mechanism for folding the straight edges, although, as will presently appear, if the work is small enough, the round corner folding mechanism may operate to do all the folding, the cases illustrated in Figs. 14 to 16 being small ones adapted to be folded entirely by the round corner folding mechanism.

40 Referring to Figs. 1, 6, 7 and 10 to 13, the construction and mode of operation of the round corner folding mechanism will be described. This mechanism comprises a work support 15, which is generally triangular in

shape; an edge guide 17 having two faces which include between them an angle equal to the angle included between the two straight edges of a board 100 which are adjacent to a round corner thereof, and a folder 19 having two faces which include between them a somewhat smaller angle. The angularly arranged faces of the edge guide 17 are connected by a face which is curved to correspond to the curve of the round corners of the boards 100, and the adjacent edge of the work support 15 is curved in the same manner at the junction of its two angularly arranged faces, while the curve at the junction of the two angularly arranged faces of the folder 19 is a recess 20 for a purpose presently to be described.

45 Normally located in spaced relation above the work support 15 is a generally triangular forming plate 21 having an outline corresponding to that of the work support 15, said forming plate being fast to the lower end of a bracket 23. A forming block 25, which cooperates with the folder to ensure that evenly spaced plaits shall be formed, is fast to one end of a rod 27 which is slidably mounted in a block 28 pivoted at 29 to the bracket 23 which is forked to receive it, a spring 31 (Fig. 2) connected at one end to a pin in the bracket 23 and at the other end to a pin in the block 28 tending at all times to swing the block in a clockwise direction about its pivot 29. A stop screw 33 threaded through a lug on the upper part of the block 28 contacts with the bracket 23 and thereby determines the angular position in which the block 28 is held. The forming block 25 is urged at all times to the right, as viewed in Figs. 10 to 13, by a coiled spring 35 and is limited in this movement by a stop 37 (Fig. 7) which is split at its lower portion and fastened by a pinch screw 38 to the split stem of an adjusting nut 41. Slidable through the block 28 and threaded through the nut 41 is a rod 39 the outer end of which is threaded through and projects beyond the forming block 25 for a purpose presently to be described. When it is desired to adjust the forming block 25 forward or back over the forming plate 21 upon which it rests, the pinch screw 38 is loosened and the nut 41 turned. When it is desired to cause the end of the rod 39 to project farther or less beyond the plaiting tool, the pinch screw is loosened and the rod 39 turned to screw it through the nut 41 and the forming block.

50 In the operation of the machine a piece of work having round corners is presented to the corner folding mechanism four times, once for each corner and is presented four times to the straight edge folding mechanism, presently to be described, once for each straight edge. In order to facilitate the proper location of the work when the round corners are presented to the corner folding

mechanism, two corner guides 43 are provided. These two corner guides are first lifted to permit the margin of the work at a corner thereof to be pushed beneath them and are then permitted to fall. The operator then manipulates the work so as to cause the edges of the board adjacent to the round corners thereof to be engaged by these corner guides. Up to this time the forming plate 21 and forming block 25 have been in their raised, inoperative positions, in which they come to rest, as shown in Fig. 2. The forming plate and forming block are now brought down so as to move through the position shown in Fig. 10 to the position shown in Fig. 11. In Fig. 10 it will be noted that the upper face of the work support or table 15 is flush with the upper surface of the edge guide 17, this relative position of parts providing a smooth surface upon which to lay the corner of the work with the margin of the cover 200 extending over the edge guide 17. The work table 15, however, is supported by a spring pressed plunger 45, its initial position with its upper surface flush with that of the edge guide 17 being determined by a stop screw 47. Consequently, as the forming plate 21 moves down to the position shown in Fig. 11, the margin of the cover is bent up above the surface of the edge guide 17 into the path of the folder 19. It should be noted that the descending forming plate first presses the work against the work support and that the work is firmly held as it is pushed down to cause the margin of the cover to be bent up. Inasmuch as the work is thus firmly clamped it is prevented from slipping away from the edge guide, and the margin of the cover is thus bent sharply about the edge of the board. The folder 19 now moves forward. As it starts its forward movement, the corner guides, having served their purpose, are raised out of the path of the folder and remain in raised position until the folder has returned to its initial position. In its forward movement the folder gathers the upstanding margin about the forming block 25, the position of parts when this has occurred being shown in Fig. 12. At this stage in the forward movement of the folder an abutment 49, which is fastened to a slide 135 to which the folder is fastened, engages the end of the rod 39 so that, during the remainder of the forward movement of the folder, the forming block 25 moves in unison with it. The space between the forming block and the folder is so predetermined (by the adjusted position of the rod 39 with respect to the forming block) that a pull is exerted upon the margin as it drags between the forming block and the folder. Continuing its forward movement, the folder bends the margin of the cover 200 over the margin of the forming plate 21; the work support is then lowered slightly to release the

pressure, after which the forming plate is withdrawn from beneath the folded over margin as shown in Fig. 13. The folder now pauses while the work support 15 is raised to press the fold against the under side of the folder, after which the work support is lowered, and the folder, forming block, forming plate, corner guides and work support return to and come to rest in the positions shown in Fig. 2. In order to hold the work firmly upon the work support, particularly during the withdrawal of the forming plate 21 from beneath the folded over margin of the cover, a presser foot 51 is mounted at the lower ends of stems 53 which pass through slots (see Fig. 1) in the forming plate 21, these stems being carried at the outer ends of curved arms 55 (Fig. 13), the other ends of which are adjustably held in pinch bearings formed in brackets 57 which are fastened to the pivoted arm 59, presently to be described, by which the forming block and forming plate are indirectly carried.

Attention is directed particularly to the cooperative action of the forming block and the folder. During the folding operation the lower portion of the margin extends upwardly and slightly inwardly, while the upper portion of the margin is flared upwardly (Fig. 12). When the margin is thus gathered about the forming block and gripped between the forming block and folder any puckers which may be present in it are small and substantially evenly spaced, whether such puckers are present depending somewhat upon the stiffness of the material of which the margin is made. As the folder and the forming block move forward and the margin is folded down flat upon the forming plate, the small evenly spaced puckers (if they are present) are flattened into small evenly spaced plaits. If substantially no puckers are present in the upstanding margin, then small evenly spaced puckers are formed progressively as the folder moves forward, and these small puckers are progressively flattened. In either case an evenly plaited finished fold results. If no forming block or other means is provided for supporting the unfolded portion of the margin during the folding operation, the unfolded portion of the margin will be bent down to some extent in advance of the folder; and comparatively large uneven puckers will be formed in it which will be converted by the subsequent action of the folder into comparatively large uneven plaits. In order to avoid this undesirable result, the forming block has an operative face which is U-shaped in horizontal cross section and flares upwardly and outwardly. When the folder moves forward into the position shown in Fig. 12, the edge of the recess 20 in the folder gathers the margin of the cover about the forming block

130

but no portion, or at most only a small portion, of the margin is bent down toward the forming plate. In order to ensure that there shall be a pull upon the margin during the folding operation, the forming block and the rod 39 are so adjusted that the space between the forming block and the folder, during the folding over of the margin, is just sufficient to permit the margin to be dragged between them.

After the four round corners have been folded in the manner described above in four operations, the four straight edges are folded by straight edge folding mechanism (Figs. 1, 2 and 3) comprising a work support or table 61, an edge guide 63 and a folder 65. The table 61 and the folder 65 of the straight edge folding mechanism are connected, as will be explained, respectively with the table 15 and the folder 19 of the corner folding mechanism so that the two tables and the two folders are operated in unison. Adjustably fastened to a rib 67 formed on the folder 65 by means of set screws 62 are a plurality of spring fingers 69 which act to bend the margin of the cover over the backing when the work is placed upon the work support 61 and pushed toward the rear of the machine so as to bring the straight edge of the work into contact with the edge guide 63. The operation of the straight edge folding mechanism is as follows: The folder 65 moves forward to fold the margin of the cover over the backing, the work support 61 first rises to press the fold and then moves slightly downward to relieve the pressure, the folder is withdrawn, and the parts come to rest in the positions shown in Fig. 2.

The general construction and mode of operation of the machine having been outlined above, a detailed description of its construction will now be given.

Referring more particularly to Fig. 2, the work support 61 of the straight edge folding mechanism is fast to a bracket 71 which is adjustably fastened by a cap screw 73 to a casting 75, an adjusting screw 77 being provided to adjust the table vertically with respect to the casting. The casting is vertically slidable in guideways formed in the frame of the machine; and the work support 15 of the corner folding mechanism has its stem 79 extending into a socket in the same casting and fastened loosely in place by a screw 81 which is threaded through a wall of the socket and extends into a groove in the stem 79. The work support 15, as has been explained, is urged upward at all times with respect to the casting 75 by the spring pressed plunger 45 as far as the stop screw 47 will permit; the groove in the stem 79 permitting such movement. When, as has been explained, the work is placed upon the work support and downward pressure applied, the work support is pushed down until the screw

81 engages the upper wall of the groove in the stem 79. The casting 75 rests upon two heavy springs one of which is shown at 83, the lower end of the springs resting upon nuts one of which is shown at 85, the nuts being threaded upon plungers one of which is shown at 87. The plungers rest upon a plate 89 which is supported by a bar 91 pivoted at its ends to the outer ends of the arms of a forked lever 93, said lever being mounted on a shaft 95 the ends of which are rotatable in alined bearings in the frame of the machine. The end of the lever 93 remote from the bar 91 carries a roll 97 which runs on a cam 99 carried by a cam shaft 101. A spring pressed plunger 103 carried by the frame of the machine ensures that the roll 97 shall at all times be held against the cam 99. With this construction, during a revolution of the shaft 101, the two tables, 61 and 15, will be moved in unison in the manner which has been explained above.

The treadle controlled mechanism for imparting one revolution to the shaft 101 and for bringing it to rest in the position illustrated has not been shown since any suitable mechanism may be employed. Preferably the one-revolution clutch which connects the cam shaft 101 with the driving shaft (not shown) is of the toe and heel type, depression of the toe end of the treadle serving to control the clutch, the heel end of the treadle being adapted when depressed to push upward the rod 105 (Fig. 1) to raise the corner guides 43. In the operation of the machine the heel end of the treadle is first depressed to raise the corner guides so that the margin of the cover may be presented beneath them and is then released to permit the corner guides to fall. After the work has been manipulated by the operator to locate it properly with respect to these corner guides, the toe end of the treadle is depressed to impart one revolution to the cam shaft 101.

The corner guides 43, which normally occupy the position shown in Figs. 1, 2 and 3, are fast to the outer ends of the arms of a forked member 107. The stem of this forked member has a groove at its rear end (Fig. 2) to receive a small rock shaft 109 which is rotatable in fixed bearings. Located one on each side of the stem are two arms 111, 113 (Fig. 1) the hubs of which are fast to the rock shaft 109, and these arms are fastened to the stem of the forked member 107 by a screw bolt 115 (Fig. 2) which passes through a bore in the arm 113, through a slot in the stem of the forked member 107 and is threaded into the arm 111, so that the three members are rigid with each other and with the rock shaft 109 when this screw bolt is tightened. When, however, the screw bolt has been loosened, the forked member, and with it the corner guides 43, may be adjusted forward or back to position the corner guides

properly. In order to facilitate such adjustment, a second screw bolt 117 carried by the arm 113 has at its end a small eccentric 119 which is received in a slot in the stem of the forked member 107. The rock shaft 109 has fast at one end (Fig. 1) an arm 121 with the under face of the outer end of which the upper end of the rod 105 is adapted to contact. When, therefore, the rod 105 is pushed up by depressing the heel end of the heel-and-toe treadle referred to above, the corner guides are raised to permit the work to be presented beneath them, and when the heel end of the treadle is released, a spring 123 pushes the rod 105 down and permits the corner guides to fall into the position shown. The one-revolution clutch is then thrown in by depressing the toe end of the treadle; and the folding operation, shown in Figs. 10 to 13, then ensues. During this operation the folder moves forward and would strike the corner guides if they were not raised and held raised. In order to raise the guides and hold them raised during the forward and backward movement of the folder there is fast to the folder slide a cam block 125 (Fig. 3) having a beveled forward end which moves beneath a horizontal roll 127 carried by one arm of the forked member 107. In order to determine the lowermost position which the corner guides will occupy when they are free to fall, a set screw 129 threaded through an arm of the forked member 107 contacts with the frame of the machine. In order to urge the corner guides downward at all times, a spring pressed plunger 131 bears against a lug 133 the hub of which is fastened to the rock shaft 109.

Turning now to the two folders, that for the round corners and that for the straight edges, the corner folder slide 135 (Fig. 2) is slideable horizontally in suitable ways formed in the frame of the machine. Formed on the under side of the slide is a slot 137 in which is received a roll 139 carried at the upper end of a lever 141 which is pivoted to the frame of the machine at 143 and carries a second roll 145 which runs in a suitable cam track 147 formed in a cam fast to the shaft 101. The track is so shaped that when one revolution is imparted to the cam shaft, the corner folder 19, which is fast to the slide 135, is moved forward into the position shown in Fig. 13, remains in that position while the fold is being pressed and then returns to its initial position shown in Fig. 10. The folder 65 of the straight edge folding mechanism is connected to the slide 135 by a pin 149 and thus partakes of the movement of the slide.

Turning now to the mechanism for operating the forming plate 21 and the forming block 25 (Figs. 1, 2 and 3) the bracket 23 by which these members are carried is slideably mounted upon a sleeve 151 the rear end of

which at its lower portion is split and provided with a pinch screw 153 (Fig. 12) which holds the sleeve adjustably upon the outer reduced end portion of a rod 155. Through the upper portion of the bracket 23 passes loosely a screw bolt 157 the end of which is threaded into a split lug 159 integral with the sleeve 151. The screw bolt is rotatable in the bracket 23 but held from longitudinal movement with respect thereto by the head of the screw and a nut 161. Consequently, by turning the screw bolt, the bracket 23 may be adjusted forward and back. A pinch screw 163 holds the screw bolt 157 in adjusted position. The rod 155 is slidably mounted in the arm 59 and has at its rear end a roll 167 which is received in an arcuate cam track 169 formed at the upper end of a lever 171. A coiled spring 173 located between the outer end of the arm 59 and a collar 175 on the rod 155 prevents chattering of the roll 167 in the cam track 169. The arm 59 at its rear end is forked and the forks terminate respectively in hubs 177, 179 which are fast to alined rock shafts one of which is shown at 181 (Fig. 3) rotatably mounted in the frame of the machine, said rock shafts each having a conical recess in its outer end to receive respectively the conical inner ends of bearing screws 183, 185. The arm 59 is lowered and raised by means of a lever 187 pivoted on one of the rock shafts 181 and having at its lower end a roll 188 which runs on a cam 189. A comparatively heavy coiled spring 191 holds the roll in contact with the cam, said spring surrounding a rod 192 one end of which is slideable through a lug 194 formed on the lever 187 and the other end of which extends into a socket formed in the frame of the machine. A screw 193 threaded through the base of the socket and engaging the head of the rod furnishes means for varying the tension of the spring 191. The upper end of the lever 187 has formed thereon a hub 195 which is normally in alinement with a hub 197 formed at the upper end of the upright arm of a bell crank lever 199; and a spring presed locking pin 201, extending through the two hubs, causes the swinging movements of the lever 187 to be imparted to the bell crank lever 199. The pin 201 has fixed in its side a small pin 203 normally received in a slot in the hub 195. By pulling the pin 201 out until the small pin 203 is out of the slot and then rotating the pin 201 a short distance, the hubs 195, 197 may be disconnected and held disconnected so that the arm 59 may be lifted by hand to give access to the forming plate 21 and forming block 25 when it is desired to remove or replace these parts. In this connection it should be noted that a cover plate 205 has at its rear end upstanding lugs which are pivoted about the alined rock shafts 181, and that, when the screw bolts 207, which hold the cover plate down, have been removed, the cover plate may be swung up to

give access to the two folders 19 and 65 and to the work support 15.

The bell crank lever 199 is connected with the arm 59 in the following manner. Referring more particularly to Fig. 1, the arm 59 has extending from one side thereof two spaced lugs 209 between which is located a block 211. A cap screw 213, the upper and lower ends of the stem of which are smooth and extend through smooth bores in the lugs 201, has its middle portion threaded through the block. The head at the upper end of the cap screw 213 and nuts 215 at the lower end hold the cap screw from longitudinal movement. The block 211 is split, as shown, and a pinch screw 217 holds the cap screw 213 from turning. The block 211 also extends between upper and lower forks at the end of the horizontal arm of the bell crank lever 199. The block is normally held down in contact with the upper face of the lower fork by a spring pressed plunger 219 which, together with its spring, is mounted in a vertical bore in the upper fork, an adjusting screw 221 being provided for varying the tension of the spring; and a set screw 223 determines the extent to which the block is permitted to rise against the action of the spring. The purpose of this connection between the arm 59 and the bell crank lever 199, which has just been described, is to permit adjustment of the position of the arm 59 so as to predetermine the position which the forming plate 21 and presser foot 51 will occupy when the arm 59 is swung down and to ensure that the forming plate and presser foot will follow the work down when the work table is moved down slightly just prior to the withdrawal of the forming plate from beneath the folded over margin. The adjustment of the arm 59 is accomplished by turning the cap screw 213. This tends, of course, to raise or lower the block 211, but, inasmuch as the block is held stationary at this time between the spring pressed plunger 219 and the lower fork of the bell crank lever 199, the arm 59 is swung up or down. Turning now to the action of the spring pressed plunger 219 at the time the work table 15 is lowered slightly just prior to the withdrawal of the forming plate 21 from beneath the folded over margin of the cover, when the arm 187 (Fig. 2) is swung in a counter-clockwise direction by the rotation of the cam 189 in the direction indicated by the arrow, the horizontal arm of the bell crank lever 199 (Fig. 1) is swung down and, through the block 211, swings the arm 59 down with it. In the course of this downward movement the forming plate 21 and presser 51 first contact with the work, as shown in Fig. 10, and then push the work and the work support 15 down into the position shown in Figs. 11 and 12. In the course of this movement the set screw 223 is brought

into contact with the block 211 and the compression of the spring which backs up the spring pressed plunger 219 is increased. Consequently when thereafter the work table 15 is lowered slightly to relieve the pressure upon the work preparatory to the withdrawal of the forming plate to the position shown in Fig. 13, the spring pressed plunger causes the forming plate and presser to follow the work down so that the presser holds the work securely while the forming plate is being withdrawn from beneath the folded over margin of the cover. 70 75

As thus far described, the machine is adapted to be used for folding book cases and similar articles having rounded corners. The machine is also adapted to fold book cases and similar articles having square corners and to this end is provided with mechanism associated with the straight edge folding mechanism for performing one step in the folding of a square corner. Referring to Fig. 4, there is shown a piece of work comprising a portion of the board 400 and cover 500 of a square cornered book case. The work has been placed upon the work table 61 and pushed forward until the margin of the cover 500 has been bent over one edge of the backing 400. As the folder 65 (Fig. 1) moves forward, this margin will be drawn tightly about the edge of the board and bent down further; and, when the work support rises, the bent over margin will be pressed firmly against and stuck to the board. The end portion 600 of the folded over margin has no board beneath it and extends over an adjacent margin which is presently to be folded over the edge 700 of the board to complete the folding of the corner. There are thus at the corner two thicknesses of the margin; and these two thicknesses at this locality are liable to cause the completely folded corner to be somewhat bumpy. In order to avoid this undesirable result, mechanism is provided for pressing the end portion 600 of the margin down upon the portion of the margin directly beneath it in the manner shown in Figs. 8 and 9. To this end the work is presented to the straight edge folding mechanism with the edge 700 of the board in line with the extreme right-hand end of the straight edge folder 65; and a presser 225, which is normally in the position shown in Fig. 4 is rotated into the position shown in Fig. 5 to force the portion 600 of the margin down upon that portion of the margin which is directly beneath it and, in doing so, to bend the portion 600 down over the edge 700 of the board in the manner shown best in Fig. 8. This bending down of the portion 600 over the edge 700 causes the edge 800 of the portion 600 to lie somewhat inside the edge 900 as shown. When now the work, in the condition shown in Fig. 8, is turned 90° and presented again to the straight edge folding 80 85 90 95 100 105 110 115 120 125 130 135 140 145 150 155 160 165 170 175 180 185 mechanism, a neatly formed, substantially smooth folded corner results as shown in Fig. 9. Two pressers 225, 325 are provided, one at each end of the straight edge folder 65 so as to permit the four corners of a piece of work to be operated upon in substantially the same manner. These fold pressers are fast respectively to shafts 227, 327 rotatable in bearings carried by blocks 229, 329, said blocks being adjustable horizontally in the frame of the machine and held in adjusted position by cap screws 231, 331 which pass through slots in the blocks and are threaded into the frame. Integral respectively with the pressers 225, 325 are pinions 233, 333 which mesh respectively with segmental racks 235, 335 carried at the outer ends of arms 237, 337, the hubs of said arms being fast to a rock shaft 239 mounted in alined bearings in the frame of the machine. Fast to the middle portion of said rock shaft (Fig. 2) is a slotted arm 241 into the slot in which extends a rectangular block pivoted at 243 to the upper end of an arm 245 which is fast 25 to a rock shaft 247. A horizontal arm 249 fast at one end to this rock shaft has, at its other end, a roll 251 adapted to run on a cam 253 carried by the cam shaft 101, said cam being shaped to cause the pressers 225, 325 30 to rotate from the position shown in Fig. 4 to that shown in Fig. 5 during the folding movement of the straight edge folder 65.

When a piece of work having square corners is to be folded, the work is presented 35 first in the manner shown in Fig. 4 to cause one straight edge to be folded and one end portion of the margin (the portion 600 in Fig. 4) to be bent down over one edge of the board into the position shown in Fig. 8. After the completion of this operation, the work is moved to the left and the fold presser 325 caused to operate upon the left-hand end portion of the margin in a similar manner. The work is then turned through 180° and the 40 opposite margin operated upon to fold it and to pinch or press the end portions of said opposite margin; after which the remaining two straight edges are presented in succession to the straight edge-folding mechanism.

It has been stated above that the four straight edges of comparatively small pieces of work may be folded by the round corner folding mechanism simultaneously with the folding of the four rounded corners. If the 45 piece of work is square or nearly so and the two legs of the folder 19 are of equal and proper length, four presentations of the work to the round corner folding mechanism will suffice to fold both the corners and the straight edges properly, provided first, that the sum of the lengths of the two legs of the folder is somewhat greater than the distance from one corner to an adjacent corner, and second, that the length of each leg is somewhat less than this distance. The sum

of the lengths of the legs of the folder should be somewhat greater than the distance from corner to corner of the work so as to ensure that the whole of the straight edge lying between two corners shall be folded. The 50 length of each leg should be less than this distance since otherwise, during the folding of a corner, the two corners which are adjacent to the one which is being folded will be partially folded in an objectionable manner by the two long legs, and neither of these two adjacent corners can thereafter be properly folded by the round corner folding mechanism.

If, however, the work is oblong, as is common, the legs of the folder should not be of equal length. With such work the legs of the folder should be of unequal lengths, one leg being shorter than the length of the finished work but longer than half said length, and the other leg being shorter than the width of the finished work but longer than half said width. In the present machine one leg of the folder 19 is made longer than the other as shown in Fig. 6, so as to enable the round corner folding mechanism to fold the entire margin of a small piece of work such as that shown in Figs. 14 to 16. Three stages in the folding of such a piece of work are shown. In Fig. 14, the corner *a* has been folded and at the same time something more than half of the margin between *a* and *b* and something more than half of the margin between *a* and *d* has also been folded. In Fig. 15, the corner *b* has been folded and at the same time the folding of the margin between *a* and *b* has been completed, and a portion of the margin between *b* and *c* has been folded. In Fig. 16, the corner *c* has been folded, the folding of the margin between *b* and *c* completed, and somewhat more than half of the margin between *c* and *d* folded. When the corner *d* is presented to the machine, the folding of the entire margin will be completed.

The illustrated machine is similar in many particulars to the machine shown, described and claimed in the application filed in the name of McIntire, which has been referred to above, and to the machines shown, described and claimed in applications Serial Nos. 656,557 and 729,930, filed respectively Aug. 9, 1923, and Aug. 4, 1924, in the name of Glass, and the subject-matter common to these applications and to the present application is not herein claimed.

Although the invention has been set forth as embodied in a particular machine, it should be understood that the invention is not limited in the scope of its application to the particular machine which has been shown and described.

Having thus described the invention, what is claimed as new and desired to secure by Letters Patent of the United States is:

1. A machine of the class described having, in combination, a work support having a rounded corner, an edge guide having a contour to correspond to that of the work support, yielding means for holding the work support with its work supporting surface normally substantially flush with the upper surface of the edge guide, a forming plate and a forming block normally held above the work support to permit the work to be placed upon the work support with the margin of the work resting upon the edge guide, means for moving the forming plate and forming block downward whereby the work is first gripped between the work support and forming plate and then moved downward to cause the margin thereof to be bent upwardly, a folder, and means for causing the folder to gather the corner portion of the margin about the forming block and bend it over the forming plate. 5
2. A machine of the class described having, in combination, a work support having a rounded corner, an edge guide having a contour to correspond to that of the work support, yielding means for holding the work support with its work supporting surface normally at a level sufficiently high to permit the margin of the work, when placed upon it, to extend over the edge guide, a forming plate having a rounded corner, a forming block located above said plate adjacent to said rounded corner and movable with said plate, means for causing the forming plate and the forming block to descend until the work has been pushed down and its margin bent up in front of the forming block, a folder, and means for moving the folder to gather the corner portion of the margin about the forming block and bend it over the corner portion of the forming plate. 10
3. Mechanism for folding the margin of an oblong piece of work having, in combination, a support for the work, a folder having legs of unequal length, one leg being shorter than the width of the finished work but longer than half said width, the other leg being shorter than the length of the finished work but longer than half said length, and means for operating said folder. 15
4. Mechanism for folding the margin of the cover of an oblong book case over the straight edges and the rounded corners of the backing thereof having, in combination, a work support having an outline corresponding to the outline of the backing at an adjacent to a corner thereof, an edge gage having a similar outline, means for holding the case upon the support, a folder having legs of unequal length, one leg being shorter than the width of the backing but longer than one-half said width, the other leg being shorter than the length of the backing but longer than one-half said length, and means for operating said folder. 20
5. A machine of the class described having, in combination, a support for the work, an edge guide, a folder, a forming plate, a member to which the forming plate is fastened, a forming block located above the forming plate, a forming block carrier pivoted to the member, means for lowering the member to bring the forming plate into contact with a piece of work on the work support and to cause the margin of the work to be bent upwardly, and means for operating the folder. 25
6. A machine of the class described having, in combination, a work support, a forming plate adapted to be brought down upon the work to hold it upon the support while the margin of the work is bent over the margin of the plate to form a fold and to be moved in a direction substantially parallel to the surface of the work support to withdraw its margin from beneath the bent over margin of the work, means for lowering the work support prior to such withdrawal, a presser foot adapted to hold the work upon the work support, and yielding means for causing the presser foot to follow the work support in its downward movement. 30
7. A machine of the class described having, in combination, a support for the work, an edge guide to which a piece of work comprising a backing and a cover may be presented in such manner as to bend the margin of the cover upward, a folder arranged to move over the edge guide, and a plurality of fingers mounted on the folder and extending over the edge guide and the work support. 35
8. A machine of the class described having, in combination, a support for the work, an edge guide to which a piece of work comprising a backing and a cover may be presented in such manner as to bend the margin of the cover upward, a folder arranged to move over the edge guide, and a plurality of fingers adjustably mounted on the folder and extending over the edge guide and the work support. 40
9. A machine of the class described having, in combination, a support for the work, an edge guide to which a piece of work comprising a backing and a cover may be presented in such manner as to bend the margin of the cover upward, a folder arranged to move over the edge guide, and a plurality of yielding fingers mounted on the folder and extending over the edge guide and the work support. 45
10. A machine of the class described having, in combination, a support for the work, an edge guide to which a piece of work comprising a backing and a cover may be presented in such manner as to bend the margin of the cover upward, a folder normally located in the rear of the edge guide and adapted to be moved over it, and a means carried by the folder and normally extending in front of the edge guide for bending the margin of 50

the cover over the backing when the work is presented to the edge guide.

11. A machine of the class described having, in combination, a work support having a rounded corner, an edge guide having a contour to correspond to that of the work support, yielding means for holding the work support with its work supporting surface normally substantially flush with the upper 5 surface of the edge guide, a presser member and a forming block normally held above the work support to permit the work to be placed upon the work support with the margin of the work resting upon the edge guide, means 10 for moving the presser member and the forming block downward whereby the body portion of the work is moved down to cause the margin thereof to be bent upwardly, a folder, and means for causing the folder to gather 15 20 the corner portion of the margin about the forming block and bend it over the body portion thereof.

In testimony whereof we have signed our names to this specification.

25 PERLEY R. GLASS.
JAMES E. MCINTIRE.
